UNITED STATES PATENT OFFICE

WALTER GUSTAV NOACK, OF BADEN, SWITZERLAND, ASSIGNOR TO AKTIENGESELLSCHAFT BROWN, BOVERI & CIE., OF BADEN, SWITZERLAND

HIGH PRESSURE STEAM GENERATOR

Application filed April 9, 1928, Serial No. 268,493, and in Germany and Switzerland April 14, 1927.

It has already been proposed to generate steam by superheating steam and passing the superheated steam through a layer of water or injecting finely divided water into the same. Fresh steam is then generated by the transmission of the heat of superheat. It has further been proposed to pass superheated steam several times through water and to superheat the steam freshly generated each time and the previously generated steam which has been cooled down by being passed through the layer of water, until finally the required quantity of working steam has been generated. For overcoming the resistance of the superheaters and that of the load of water and to bring the steam into circulation, various expedients are required which entail certain disadvantages. If, for instance, the steam be generated in a single heat exchange body, it is necessary to provide a separate pump for circulating the steam which acts as the heat carrier and for various reasons must be many times the quantity of useful steam, which pump requires a relatively large amount of energy and detrimentally affects the efficiency of the plant to a considerable extent through the unavoidable leakage losses. If, on the other hand, motion be imparted to the steam by generating in a separate boiler so-called exciter steam at a higher pressure and by allowing the said exciter steam to flow with its own drop in pressure successively through several superheaters and water spaces, fresh steam being generated in each water space by the heat of superheat, the circulating pump becomes superfluous, it is true, but a larger number of pressure containers becomes necessary which increase the cost of the plant, require more space and introduce certain working difficulties. The present invention relates to a method of producing steam, more particularly high pressure steam (above 50 atms.) by means of superheated steam as the heat carrier, in which the drawbacks referred to are avoided. The method consists in this, that in an "exciter boiler" a relatively small quantity of steam (less than half the quan-

tity of working steam) is generated, which flows under its own drop in pressure through a considerable number of superheaters or groups of superheaters located one behind the other, which are provided at any number of points, but at least two points, with devices, by means of which water is introduced in a finely divided state. By withdrawing the superheat, fresh steam is generated from the introduced water, which steam is superheated together with the now saturated, previously generated steam and so on until the desired quantity of working steam is obtained.

Figure 1 shows diagrammatically the arrangement of the steam generator according to the invention.

Figure 2 is a diagrammatic section through the evaporator and the steam and water collector with the water injector pump.

Figure 3 shows the section through an evaporator with filling bodies for increasing the water surface.

Figure 4 the same with filling bodies to act as water separators.

Figure 5 the arrangement of the evaporators with a device for injecting addition water,

Figure 6 diagrammatical arrangement of the steam generator with pump for the injection water and a heat pump, through which the exciter steam can be generated (instead of the exciter steam boiler).

In Fig. 1 of the accompanying drawings the steam generator is shown diagrammatically for carrying out the method. In this figure, 1 is the furnace space. In this space is the exciter boiler 2 and 3 in which the small quantity of exciter steam is produced and the remainder of the feed water may be preheated. The exciter steam flows thence under its own pressure through the pipes 6 by way of a throttling point 29 and a shutting off valve 33 to the first superheater 7, is highly superheated in the said superheater and passes to the first evaporator 13, where the heat of superheat is withdrawn from it by injected water which has been preheated almost up to evaporation

temperature. By this superheating heat fresh steam is generated from the injected water, which steam together with the exciter steam which has been cooled down to approximately saturation temperature flows to the next superheater 8. Fresh superheating heat is supplied to this superheater, which enables an increased quantity of steam to be generated in the next evaporator 14 from the water injected into the steam. This is repeated until finally the required quantity of working steam is obtained.

The water to be injected can, as already stated above, be withdrawn from the exciter boiler 2, 3 lying in the furnace space, which therefore in the present instance also acts as water heater, through the pipe 5 by way of a shut-off valve 32. The fresh water itself is introduced at 4. The whole of the steam generated leaves the last evaporator 18 by way of the valve 31 and passes through a final superheater 28, where it is brought up to the degree of superheat required for working purposes, to the place where it is to be used. The other parts shown in Fig. 1 and not hitherto described will be alluded to later on.

While Fig. 1 shows diagrammatically the steam generator seen from above, Fig. 2 shows the evaporator part with the container diagrammatically in side elevation partly in section. 13 to 18 are the evaporators which receive their injection water through the pipe 5 for instance from the water preheater of the exciter boiler (not seen in this Figure). The water is injected through nozzles 40 in a finely divided state, so that it offers a large surface to the superheated steam entering at 41. At 42 wire sieves are provided which hold back large drops and cause them to be divided up and evaporated. The cooled and freshly generated steam leaves the evaporators at 43, whence it flows to its particular superheater. In front of the outlet parallel sheet metal members may be provided, on which any water which may be carried along separates off.

The object of injecting in a very finely divided state is, as already stated, to present large surfaces for making a rapid absorption of heat possible. Instead of injecting in a finely divided state through nozzles the spreading of the water to be evaporated over a large surface may be effected for instance by suitable filling pieces provided in the evaporating bodies. This expedient has the advantage that in place of a nozzle of small bore ordinary roses can be used, which are less liable to become stopped up, and that the carrying along of drops is more readily prevented. These filling pieces may consist of small cylinders (so-called Raschig-rings) and are made of a material which is a very good heat conductor. In

Figs. 3 and 4 evaporators of this kind are shown in section. 50 is the body of the evaporator, 51 are filling pieces. They rest on a grid 52 below which the superheated steam is admitted at 53. The water enters through a rose 54 and is distributed over the filling pieces, whereby it presents a large surface to the steam meeting it in counterflow. The cooled and freshly generated steam flows off at 55 while superfluous water is drained at 56.

The constructional form shown in Fig. 4 differs from that of Fig. 3 in this, that the filling forms two layers 51 and 57, having a free space between them, into which the rose 54 opens. Thus, only the lower part is played on, the upper part acting as a steam and water separator. In addition it may be heated by the admission of superheated steam from the pipe 53 or 58, so that any adhering drops will be evaporated.

It is important that the steam generator under discussion should always be operated in such a manner that the final temperature of the superheating in each separate superheater and the quantity of water injected bear a certain relation to one another. When too little water is supplied, the consequence will be that the steam introduced is cooled off too little and will be superheated too strongly in the next superheater. Too much water on the other hand has the disadvantage that water may easily be carried along and any impurities may be deposited in the superheater tubes, rendering the latter foul. Another disadvantage may be that unnecessary pumping work has to be performed. One possible manner of regulation is provided by the temperature of the superheated steam itself. For instance, a thermostat may be provided which is influenced by the temperature of the steam at any point, more particularly the temperature at the end of the superheater following an injection nozzle or group of nozzles. In Fig. 1 the arrangement of such a method of regulation by a thermostat is shown. In this figure 19—23 represent thermostats of any known constructional form which act on cut-off devices of any kind for the water supply pipes of the evaporators 13—18. If the temperature at the end of a superheater be too high a thermostat operates the inlet valve in such a manner that more water will be admitted and vice versa. As already stated above, the regulating device may be suitably so adjusted that in every case only so much water is injected that the steam is still superheated when leaving the heat exchange body (evaporator), so as to prevent the separation of water as far as possible.

When, however, the separation of water is prevented with certainty by means such as those shown more particularly in Fig. 4 and described above, water in excess up to a

certain amount may be introduced. Thus, for instance, the thermostat regulation may be caused to act on only a portion of the water supply, by providing two injection 5 nozzles or roses or two groups of the same for each evaporator, one of which supplies the injection water to be evaporated in normal working, while the other, which is operated by a thermostat or the like, comes into 10 operation only in exceptional cases. Such exceptional cases may be either loads exceeding a predetermined load or disturbances in the working, for instance a stopping up or a fracture of the uncontrolled 15 injection devices. Fig. 5 shows semi-diagrammatically the arrangement for the combined method of working. In this figure, 20 50 are the evaporator bodies, 51 the fillings, at 54 water enters through a rose, is distributed over the filling pieces, and withdraws the superheating heat from the highly 25 superheated steam. The supply to this rose is in this instance, however, so regulated that a predetermined quantity of water flows to it, which remains constant over a wide working range. The water which does not evaporate flows away at 56. Should the water introduced through the roses 54 be for any 30 reason insufficient, so that in the subsequent 35 superheater 60 or 61 the superheating exceeds an admissible amount, the thermostat at 62 or 63 becomes operative and automatically opens the valve 64, 65 which allows more water to flow in until the superheating 40 temperature has sunk again to the predetermined maximum amount.

Should it not be possible to evaporate all the injected water at once or if the water be purposely injected in excess, a smaller 45 or larger quantity of water will accumulate in the bottom of the evaporator. This water contains considerable quantities of energy in the form of heat and pressure. It is therefore of particular importance that it shall be taken away and collected without loss. Thus, a further object of the present 50 invention is to provide a method of conveying away this excess water from the bodies in which the injection and evaporation takes 55 place through suitable devices and of collecting it for further use. For this purpose the evaporator bodies may be provided in their lower parts with a small collecting space which is connected with a larger collecting drum common to all the evaporators. This connection is by way of a float-operated 60 valve or by a trap. The latter must be so designed that while sufficient water can flow out, the passage of large quantities of steam, for instance from one evaporator to the next, is prevented. The common collecting drum is represented in Fig. 1 as the drum 25, and the common outflow pipe by 24. In Fig. 2, 45 are the traps which 65 open into the collecting pipe 46. The com-

mon collecting drum is shown in section at 47. In Fig. 5 the outlets 56 are shown but not the collecting pipe and the drum.

The collecting drum in which the excess injection water is collected may serve a further purpose. It can also be used as a steam collector or a buffer vessel for equalizing the fluctuations in the steam consumption. If the superheaters and the evaporators in the new steam generator be regarded as corresponding in their action to the water tubes of ordinary steam generators, the accumulator represents the upper and lower drums of ordinary boilers, that is the parts by means of which the water to be evaporated and the already generated steam can be stored. Through the last evaporator 18 being connected as shown in Fig. 1 by the pipe 34 with the distributor pipe 26, while on the other hand the last superheater 28 is connected with the steam dome 27, steam may, when there is a momentary excess of steam, be passed into the water space of the drum 25 and be condensed there with an increase in pressure. Conversely, when there is a momentary lack of steam, steam may be withdrawn at 27 from the drum, the pressure in the drum decreasing. The water which was injected in excess into the heat exchange bodies (evaporators) and passed away to the drum may be used again wholly or in part for injection purposes. For this purpose it must be brought up to the requisite injection pressure by a pump. This mode of operation is shown in the diagrammatic view in Fig. 2, in which 46 represents the pipe for conveying away the excess of water and 47 the drum, while the pump referred to is shown at 48 and the motor for driving it, for instance an electric 100 motor at 49. The suction pipe of the pump is connected to the drum and the delivery pipe leads to the evaporators 13-18 which may also be fed by the pipe 5 from the exciter boiler. When the injection water is 105 delivered entirely by water which the pump 48 has withdrawn from the drum, the valve 70 is closed and the feed water which has been preheated in the exciter boiler or fresh feed water is delivered directly through the 110 pipe 71 to the drum. In this case a float-operated valve 72 is required which regulates the water level in the drum 47.

The pump 48 may with advantage be driven by a steam turbine 73. For ensuring reliable working, in addition to the steam turbine an electric motor may be coupled up as well, which runs idle and is only supplied with current when the number of revolutions of the pump has sunk below an admissible amount.

For ensuring reliable working and the proper functioning of the new steam generator, various details are required which form further objects of the present inven- 130

tion. Thus, the heat exchange bodies (evaporator bodies) must be provided with mud separators. Furthermore it may be necessary more particularly when the water is introduced in a finely divided state by means of injection nozzles, that the injection water shall have a considerably higher pressure than the steam. When the exciter steam and the injection water are delivered from the same boiler, for instance as shown in Fig. 1 at 2 and 3, in other words, when the water and the steam are at the same pressure, the pressure of the steam must be artificially reduced for the evaporators.

15 This may be effected by a reducing valve, indicated by way of example in Fig. 1 at 29.

From the manufacturing point of view it is an advantage for all the parts used to have the same dimensions. This can be effected by all the superheater parts having the same surface and being grouped about the furnace and in the flues in a similar manner. Furthermore, all the superheaters or superheater groups may be arranged one behind the other in such a manner, and their superficial area and the cross-sectional areas of the steam passages may be made such, for instance by placing several superheater parts in parallel, that for each superheater 20 or group of superheaters the evaporator bodies and the injection nozzles will be of the same size and construction.

The new steam generator provides the further great advantage that the boiler parts containing considerable quantities of water and steam, as for instance the exciter boiler and the accumulator, are separate from the superheater tubes, i. e. the parts actually serving the purpose of steam generation and lying in the flues. This makes it possible to disconnect some parts entirely without having to interrupt the operation of the plant and to provide the superheater tubes with non-return valves or valves which automatically disconnect a superheater tube from the rest of the steam generator on a fracture occurring in the said tube.

For the same reason the steam generator 30 may be worked as a rapid evaporator and a peak boiler. The superheater tubes in which the steam is actually generated may be made of smaller diameter than the water tubes of ordinary steam boilers. Hence, 35 the thickness of the wall of these tubes may be small, even for high steam pressures. The weight of the heating surfaces is for this reason exceedingly small compared with a water tube boiler having the same 40 heating surface area. The water space and the masses of the containers which in an ordinary boiler are required for containing these quantities of water are also done away with. With suitable firing, for instance coal dust, the present steam generator can im-

mediately commence to generate steam, as only the small masses of tubes of the superheater have to be brought up to the working temperature, while the generation of steam commences immediately with the injection of the water into the superheated steam. Where steam is required immediately, the steam will in general be drawn immediately from the evaporators and superheaters. When, however, the drum is under pressure or there is sufficient time to bring it up to pressure, the steam may be withdrawn by way of the said drum. Thus, the steam generator according to the present invention may be worked, as required, as a tubular boiler pure and simple or, by connecting up the accumulator-like steam collector, as a boiler having a large water space.

In order to facilitate the mode of operation described above, it will be seen to that the drum is always under pressure, i. e. that the water in it is and remains at a temperature corresponding approximately to the working steam pressure. For this purpose, when shutting off the boiler, the remaining steam will be passed into the water space and during working a portion of the steam will be allowed to pass through the water space of the drum.

In order that, when starting up, it may not be necessary to wait for exciter steam to be generated in the exciter boiler, the exciter steam may in many cases be withdrawn from other sources, for instance boilers having the same working pressure which are in operation at the time. A further very useful method is the use of a so-called heat pump. Such a heat pump, more particularly when it should be a piston pump, makes it possible, even when the contents of the drum are considerably cooled down, to obtain steam from the water in the accumulator by suitably reducing the pressure and to compress the same to the pressure required in the superheaters. The heat pump may thus render the exciter boiler superfluous not only when starting but also during normal working.

In Fig. 6 the steam generator is again shown diagrammatically. The same parts have the same reference numerals as in Fig. 1. Fig. 6 also shows the connection of the pump for the injection water, which is withdrawn from the drum and the motor for driving the pump. In addition to this, 75 is the suction pipe for the heat pump which itself has the reference numeral 76. 77 is the motor for driving the pump. The figure also shows a connecting pipe 78 which can be shut off by a valve 79 and enables excess steam or the steam generated after the withdrawal of steam has ceased to be conveyed through all the superheaters and condensed in the water space of the drum. As this

drum in contradistinction to the upper drum of normal boilers is capable of working with a very variable water level, it is possible, for instance when a large quantity of steam has 5 to be received by the drum, to prevent an excessive increase in pressure by feeding in cooled water.

Instead of being filled with water the drum might also be filled with liquid having 10 a high boiling point in order to obtain high temperatures with only a small pressure in the drum. In this case the superheated steam must flow in the interior in coils, where it condenses and gives off its heat to 15 the liquid having a high boiling point. For generating additional steam or for pre-heating the injection water, water is forced through these coils and the stored heat is in this way withdrawn from the liquid having 20 a high boiling point.

What I claim is:

1. In an apparatus of the class described, a steam and water drum, a series of alternately connected substantially dry evaporators 25 and superheaters, an exciter boiler acting as an initial steam source and delivering steam through a superheater into the first of said evaporators, means for delivering water from said steam and water drum individually and in finely divided form into said 30 evaporators, means for returning surplus water from said evaporators to said steam and water drum, and means for delivering steam from the last of said series of 35 evaporators to a place of consumption.

2. An apparatus as described in claim 1, filling elements in said evaporators adapted to distribute the water.

3. In an apparatus as described in claim 40 1, additional means for delivering water individually into said evaporators from said exciter boiler.

In testimony whereof I have signed my name to this specification.

45 WALTER GUSTAV NOACK.
